HOUSING FOR A RADIANT HEATER

Dee Lane Jenner, La Canada, Calif., assignor to Hi-Shear Corporation, Torrance, Calif., a corporation of California

Filed Aug. 11, 1964, Ser. No. 31,239

Term of patent 14 years

(Cl. D81—10)

FIG. 1 is a perspective view of a housing for a radiant heater; and

FIGS. 2 and 3 are left-hand and right-hand views, respectively, of FIG. 1.

The side opposite that shown in FIG. 1 is a mirror image thereof with the exception that there is no circular opening.

I claim:

The ornamental design for a housing for a radiant heater, as shown and described.
